[57] CLAIM

The ornamental design for a rollerskate brake, as shown and described.

DESCRIPTION

FIG. 1 is a left rear perspective view of a one embodiment of a rollerskate brake showing my new design;

FIG. 2 is a right rear perspective view thereof;

FIG. 3 is a top view thereof;

FIG. 4 is a bottom view thereof;

FIG. 5 is a right side elevational view thereof;

FIG. 6 is a left side elevational view thereof;

FIG. 7 is a front elevational view thereof;

FIG. 8 is a rear elevational view thereof;

FIG. 9 is a right rear perspective view of an alternative embodiment of my new design of FIGS. 1-8 thereof;

FIG. 10 is a left perspective view thereof;

FIG. 11 is a top plan view thereof;

FIG. 12 is a bottom plan view thereof;

FIG. 13 is a right side elevational view thereof;

FIG. 14 is a left side elevational view thereof;

FIG. 15 is a front elevational view thereof;

FIG. 16 is a back elevational view thereof; and,

FIG. 17 is a sectional view taken along the line 17—17 of FIG. 13.
